UNITED STATES PATENT OFFICE.

HARRISON M. TURNER, OF KANSAS CITY, MISSOURI.

TRACTOR.

Application filed May 12, 1921. Serial No. 468,819.

To all whom it may concern:

Be it known that I, HARRISON M. TURNER, a citizen of the United States, residing at Kansas City, in the county of Jackson and 5 State of Missouri, have invented a certain new and useful Improvement in Tractors, of which the following is a specification.

My invention relates to improvements in tractors.

10 The object of my invention is to provide a novel tractor which is simple in construction, relatively cheap to make, which is easy to manipulate, which is durable and not liable to get out of order, which can be reversed in its direction of movement in small space and which is efficient in operation.

The novel features of my invention are hereinafter fully described and claimed.

15 In the accompanying drawings, which 20 illustrate the preferred embodiment of my invention,

Fig. 1 is a side elevation of my improved tractor.

Fig. 2 is a central longitudinal sectional 25 view of the same.

Fig. 3 is a plan view, reduced, partly broken away, of the same.

Fig. 4 is an enlarged vertical sectional 30 view on the line 4—4 of Fig. 3.

Fig. 5 is an enlarged vertical sectional 35 view, partly broken away, on the line 5—5 of Fig. 10.

Fig. 6 is a top view, partly in plan and partly in horizontal section and partly 40 broken away, of my improved tractor.

Fig. 7 is an enlarged vertical sectional view on the line 7—7 of Fig. 8.

Fig. 8 is an enlarged cross section on the 45 line 8—8 of Fig. 6.

Fig. 9 is a front end elevation of the tractor.

Fig. 10 is a vertical sectional view on the line 10—10 of Fig. 1.

Fig. 11 is an enlarged cross section on the 45 line 11—11 of Fig. 6.

Fig. 12 is an enlarged sectional view on the line 12—12 of Fig. 11.

Fig. 13 is an enlarged vertical sectional 50 view on the line 13—13 of Fig. 10.

Fig. 14 is an enlarged vertical sectional view on the line 14—14 of Fig. 10.

Similar reference characters designate similar parts in the different views.

The tractor is provided with a single relatively large traction wheel, comprising an 55 annular rim 1 and two circular side plates 2 which are spaced apart so as to form with the rim a hollow wheel, the plates 2 being secured to the rim 1 adjacent to the edges thereof by bolts 3.

60 A horizontal rectangular main frame 4 is provided at its middle portion with two transverse tubular trunnions 5 and 6, secured rigidly to the frame and disposed in alinement with each other and on which the 65 two side plates 2 are respectively rotatably mounted.

65 Mounted in the traction wheel is a motor, such as an explosive engine, having a body 7, from the center of which upwardly extend two standards 8, through which respectively extend and to which are rigidly attached the trunnions 5 and 6, and by which the body of the motor is pivotally suspended 70 in the traction wheel below the axis thereof. 75

The motor is provided with one or more upright cylinders 9, in which are respectively reciprocatively mounted two pistons 10, connected in the usual manner by two connecting rods 11, with two cranks 12 of a horizontal longitudinal crank shaft 13, which is 80 rotatably mounted in bearings 14, which are held between the body 7 and a crank case cover 15, which is bolted to the lower side of the body 7.

85 For supporting some of the weight of the motor so as to relieve the trunnions 5 and 6 of a portion of the weight, there are provided a plurality of vertical coil springs 16, the upper ends of which bear against the 90 under side of the cover 15 and are located in recesses provided in the cover, and the lower ends of which are mounted in rings 17 which are rigidly secured to the upper side of a weight 18, which is carried upon two pairs 95 of end rollers 19, and two central flanged rollers 20 mounted on two annular tracks 21 on the inner periphery of the rim 1. As the traction wheel travels along, the weight 18 is adapted for travel by means of the 100 rollers 19 and 20 on the annular track 21.

The body of the motor is provided at its

forward and rear ends respectively with two upwardly extending standards 22, having mounted respectively thereon two boxes 23 in which is rotatably mounted a longitudinal horizontal driven shaft 24, which has rigidly secured to it a sprocket wheel 25 which is connected by a chain belt 26 with a sprocket wheel 27, which is rigidly secured to the crank shaft 13.

10 Rigidly secured on the crank shaft 13 adjacent to the respective ends thereof are two fly wheels 28.

When the motor is operated, the driven shaft 24 is rotated in one direction by the sprocket wheels 25 and 27 and the chain belt 26.

In order that the traction wheel may be revolved in both directions, one of the side plates 2 has rigidly secured to its inner side 20 an annular rack 29 which meshes with two spur gear wheels 30 and 31, which are rotatably mounted on the shaft 24 adjacent to the respective ends thereof.

25 Splined on the shaft 24 so as to slide thereon and to be rotatable therewith are two clutch members 32 and 33, arranged to have frictional driving engagement with the inner ends of the hubs of the gear wheels 30 and 31 respectively.

30 When the clutch member 32 is engaged with the gear wheel 30, and the motor is operated, the traction wheel is revolved in one direction. When the clutch member 32 is moved to the release position and the clutch member 33 is moved into driving engagement with the gear wheel 31, the traction will be revolved in the opposite direction.

35 For alternately shifting the clutch members 32 and 33, into and out of engagement with the gears 30 and 31, and for shifting the clutch members to the neutral position, shown in Fig. 2, there are provided two upright levers 34 and 35, which are respectively pivoted to brackets 36 and 37, which 40 are secured to the body 7. The levers 34 and 35 respectively carry two rings 38 and 39 which are respectively rotatably mounted in peripheral grooves provided therefor in the clutch members 32 and 33.

45 A longitudinal connecting bar 40 is respectively pivoted at its ends to the upper ends of the levers 34 and 35. By reciprocating the bar 40, the levers 34 and 35 may be 50 swung so as to move the clutch members 32 and 33 simultaneously on the driven shaft 24.

55 For reciprocating the connecting bar 40, it is pivoted near its middle portion to the upper end of a crank arm 41, the lower end of which is rigidly attached to a tubular shaft 42 extending through the trunnion 5 and to the outer end of which is rigidly attached the upper end of a crank arm 43, the lower end of which is pivoted to a longitudinal manually operated bar 44,

60 65 which is pivoted to the lower ends of two

swinging links 45, the upper ends of which are pivoted to the frame 4 at opposite sides of the axis of the traction wheel.

By reciprocating the bar 44, the connecting bar 40 may be moved to engage and disengage the clutch members 32 and 33.

70 For yieldingly holding the crank arm 41 in the neutral position, shown in Figs. 2, and 5, the lower end of the crank arm 41 is provided with a V-shaped notch 46 which is 75 adapted to receive a wedge shaped projection 47 provided on the free end of a spring plate 48, the other end of which encircles a horizontal pin 49 extending inwardly from the adjacent standard 8. The spring plate 80 48 is held between two inwardly extending pins 50, Fig. 5, mounted in the adjacent standard 8.

85 For yieldingly holding the crank arm 41 in either of its two driving positions, there is provided an upright coil spring 51, the upper end of which is attached to a horizontal pin 52 mounted in the crank arm 41, and the other end of which is attached to an inwardly extending pin 53 located in the adjacent standard 8 in the same vertical plane as the axis of the shaft 42. When the crank arm 41 is in the neutral position shown in Fig. 2, and in solid lines in Fig. 5, the pins 52 and 53 are in the same vertical plane.

90 When the crank arm 41 is swung to the right or left or the neutral position, the spring 51 will tend to hold the crank arm in the position to which it has been swung. The upper end of the spring 51 crosses the vertical plane of the shaft 42, when the crank arm 41 is oscillated between its two driving positions.

95 To revolve the traction wheel in one direction, the operator shifts the bar 44 in one direction from the neutral position. To revolve the traction wheel in the opposite direction, the bar 44 is shifted in the opposite direction from the neutral position.

100 The tractor is provided with a draft frame comprising two end portions 54 and 55, and an intermediate portion 56. The rear end portion 55 is adapted to be supported upon a carrying wheel 57, which is adapted for travel on the ground.

105 The front end portion 54 is preferably a substantially arcuate bar, the upper end of which is pivoted on a vertical shouldered bolt 58 which is fitted rigidly in a vertical threaded hole in an arcuate plate 59, the ends of which are attached to the upper side of the horizontal portion of the frame 4.

110 The bolt 58 is located in the vertical plane of the axis of the traction wheel, and the semi-circular plate 59 and the plate 54 are concentric with each other and with the rim 1.

115 The front end of the intermediate portion 56 of the draft frame is pivoted by a horizontal transverse bolt 60, so that the por-

tion 56 and with it the rear portion 55 may be swung vertically from the position shown in solid lines in Fig. 1, to the position shown in dotted lines in said figure, for the purpose of unlocking the draft frame from the main frame, to enable the draft frame to be swung from the position shown in solid lines in Figs. 1, 2 and 3, to the position diametrically opposite, as shown in dotted lines in Fig. 3.

For releasably locking the draft frame in either of the two positions shown in Fig. 3, the horizontal portion 4, of the main frame, has mounted on it adjacent to its respective ends two upwardly extending members 61 and 62, which form two upwardly extending abutments adapted to enter a vertical slot 63 in the intermediate portion 56, Fig. 2, and Fig. 4.

Extending upwardly from the portion 56 are two projections 64 and 65 in which are respectively provided holes in which is slidably mounted a horizontal longitudinal rod 66, the rear end of which is attached to a right angled bolt 67, the horizontal arm of which is adapted to enter a slot 68 provided in each of the members 61 and 62. A coil spring 69 encircles the rod 66 and bears at one end against the projection 65. The other end of the spring 69 bears against a collar 70 secured rigidly to the rod 66. The tension of the spring 69 is such as will normally force the bolt 67 into the adjacent slot 68, when either member 61 or 62 is inserted through the slot 63, as shown in Fig. 4.

For withdrawing the bolt 67 from the slot 68, the upwardly extending arm of the bolt 67 has attached to it one end of a rod 71, the other end of which is pivoted to a lever 72, which is pivoted by a horizontal transverse pin 73 to a bracket 74 secured to the frame portion 55, Fig. 2. When the lever 72 is swung to the locking position, shown in Fig. 2, the rod 71 will be below the pivot pin 73, thus securely holding the lever from accidental displacement from the locking position. When it is desired to unlock the draft frame from the main frame so that the draft frame may be swung on the bolt 58 from the position shown in solid lines in Figs. 1, 2, 3 and 6 to the position shown in dotted lines in Fig. 3, the lever 72 is swung upwardly and to the right, as viewed in Fig. 2, thereby forcing the bolt 67 out of the slot 68. The draft frame is then lifted at its rear end, thus swinging the portion 56 on the bolt 60 to the position shown in dotted lines in Fig. 1, in which position, the portion 56 will clear the member 61. The draft frame may then be swung horizontally in either direction on the bolt 58 to the position shown in dotted lines in Fig. 3. In this position, the abutment member 62 will enter the slot 63. Then by swinging the lever 72 to the locking position shown in Fig. 2, the bolt 67 will enter

the slot 68 in the member 62. The spring 69 will assist the lever 72 in moving to this position.

In order that the frame portion 55 may swing on a horizontal longitudinal axis with respect to the intermediate frame portion 56, to accommodate the carrying wheel 57 to inequalities of the ground, the portion 56 is provided with a rearwardly facing cup shaped member 74 in which is revolvably fitted a forwardly facing cup shaped member 75 which is provided at the front end of the frame portion 55. A longitudinal horizontal bolt 76 extends centrally through the members 74 and 75 and has encircling it a coil spring 77 the front end of which bears against the member 75 and the rear end of which bears against a nut 78 mounted on the rear end of the bolt 76.

This construction permits the frame portion 55 to have an oscillatable movement on a longitudinal horizontal axis with respect to the intermediate portion 56.

For steering the tractor, the carrying wheel 57 is mounted on a U shaped yoke 79 between the arms thereof. The upper central portion of the yoke 79 is rigidly secured to the lower end of a vertical steering shaft 80 which is rotatably mounted in the frame portion 55. A transverse handle bar 81 is secured to the upper end of the shaft 80 adjacent to a seat 82, mounted on the frame portion 55 at the rear of the shaft 80, upon which the operator sits in operating the tractor.

As a partial counterbalance to the weight of the frame portions 55 and 56, the lower rear end of a coil spring 83 is secured to the upper part of the frame portion 55 adjacent to the shaft 80, and extends upwardly and forwardly to the curved plate 54 to which the front end of the spring is attached. The spring 83 has a lifting tendency on the frame portion 55. In the coil spring 83 is mounted a rod 84, the lower end of which is attached to and bears against the frame portion 55. When the portion 55 is swung upwardly so as to be free of the abutment 61 or 62, as the case may be, the upper end of the rod 84 will bear against a bolt 85 which attaches the upper end of the spring 83 to the plate 54, thereby limiting the upward swinging of the frame portions 55 and 56.

When it is desired to use the tractor for plowing, the frame portion 55 may have pivoted to it on a transverse bolt 86 mounted in the frame portion 55, the front ends of one or more plow beams 87, to the rear ends of which are respectively secured two outwardly turned plow shares 88 and 89.

For lifting the plow beams 87, they have respectively attached to them the lower ends of two chains 90, the upper ends of which are respectively attached to two rearwardly extending arms 91 of two levers 92, each

pivoted to the frame portion 55 by a transverse pin 93, and each having pivoted to it the usual hand operated lever 94 which is connected by a rod 95 with a bolt 96 adapted to enter a toothed segment member 97 secured to the frame portion 55. The usual coil spring 98 on the rod 95 normally forces the bolt 96 into engagement with the segment 97, Fig. 2.

In order that the motor may be cranked in starting it, the outer end of a shaft 99, rotatably mounted in and extending through the trunnion 6, is squared so as to be engaged by a cranking wrench, not shown, of the usual type. Rigidly secured to the inner end of the shaft 99 is a bevel gear wheel 100, which meshes with a bevel gear wheel 101 which is rotatable on the driven shaft 24 and which has mounted in it a pin 102 on which is pivoted a pawl 103 which is adapted to engage a ratchet wheel 104 which is rigidly attached to the shaft 24. A spring 105 mounted at one end on a pin 106 secured to the gear wheel 101 bears at its other end upon the pawl 103 and normally holds the latter engaged with the ratchet wheel 104. The spring 105 is disposed between two pins 107 mounted in the gear wheel 101 and which retain the spring in operative position on the pin 106. The disposition of the pawl 103 and the ratchet teeth of the ratchet wheel 104 is such that, when the shaft 99 is turned in a direction such that the pawl has driving engagement with the ratchet wheel 104, the shaft 24 will be turned in a direction such that the engine will be cranked. In order that the shaft 99 may be used for power purposes, it has secured to it a pulley 108 from which power may be taken off for operating any machine that it may be desired to operate. For this purpose, the pawl 103 has through it a hole adapted to receive a bolt 109, Fig. 11, which is adapted to be mounted in a threaded hole in the gear wheel 101. The position of the pawl when so held by the bolt 109 is such that the pawl is engaged with and can not slip over the teeth of the ratchet wheel 104. The gear wheel 101 will thus be locked to the shaft 24 so as to turn therewith.

In the operation of the tractor, when it is desired to go ahead or to the right, as viewed in Fig. 2, the bolt 109 is withdrawn, and the shaft 99 cranked so as to start the engine, the shaft 13 of which will turn counterclockwise, when looking forwardly at the rear end of the crank shaft 13. The shaft 24 will be driven in like direction by the chain belt 26 and the sprocket wheels 25 and 27. The operating bar 44 is then shifted from the neutral position rearwardly so as to engage the clutch member 33 with the gear wheel 31, and the latter will revolve the traction wheel forwardly or clockwise, as viewed in Fig. 2. The levers 92 are then

operated to lower the plow shares 88 and 89 into operative position upon which the plowing will begin.

When the end of the row is reached, or when it is desired to drive the traction wheel in the opposite direction, the bar 44 is shifted to neutral, and the lever 72 is swung to release the frame portion 56 from locked engagement by the bolt 67 with the abutment member 61. The frame portion 55 and the frame portion 56 are then swung upwardly so as to have the portion 56 free from the abutment member 61, after which, the draft frame is swung on the bolt 58 to the position shown in dotted lines in Fig. 3. The lever 72 is then swung to engage the bolt 67 with the abutment member 62. The bar 44 is then shifted from neutral to the right, as viewed in Fig. 1, thereby shifting the clutch member 32 into driving engagement with the gear wheel 30, and the latter will revolve the traction wheel counterclockwise, as viewed in Fig. 2.

From the foregoing it will be noted that when the tractor is to be driven back and forth it is not necessary to turn the traction wheel horizontally, but the draft frame is swung from one position to the other and the bar 44 is operated to shift the clutch members to change the direction of rotation of the traction wheel.

When it is desired to have the motor revolve the shaft 99, the clutch members are shifted to neutral, and the bolt 109 is inserted through the pawl and into the gear wheel 101, the motor being slowed down sufficiently to permit the insertion of the bolt.

The weight 18 in addition to serving as a support for the springs 16, also serves as a stabilizer for the traction wheel to prevent the latter tipping over sidewise. The suspending of the motor below the axis of the traction wheel also serves to stabilize the wheel. When the engine or motor is started, it has a tendency to swing upwardly around the axis of the traction wheel, due to its geared connection with the latter, but owing to the rigid connection of the motor standards 8 with the frame 4, by means of the trunnions 5 and 6, this tendency is overcome, and the driving thrust of the engine is transferred to the ground through the frame 4, the trailing auxiliary frame and the carrying wheel 57.

This action takes place when the tractor is driven forwardly in either direction.

In addition to the springs 16 serving as an auxiliary support for the motor, through the intermediacy of the stabilizing weight 18, said springs serve also as a flexible yielding means for holding the motor and weight in substantial vertical alignment with each other.

I do not limit my invention to the struc-

ture shown and described, as many modifications, within the scope of the appended claims, may be made without departing from the spirit of my invention.

5. What I claim is:—

1. In a tractor, a revoluble traction wheel having an annular rack, a motor in said wheel, means supported by the wheel for supporting the motor, a pair of gear wheels

10 rotatable on said supporting means and meshing with said rack at diametrically opposite points thereon, and manually controlled means actuated by the motor by which the gear wheels may be alternately rotated, substantially as set forth.

15 2. In a tractor, a revoluble traction wheel having an annular rack, a motor in said wheel having a body, a main frame supported by the wheel and supporting the

20 motor body, a driven shaft rotatable on said motor body, means actuated by the motor for rotating said shaft, two gear wheels meshing with said rack at opposite sides respectively of the axis of said wheel and rotatable

25 on said shaft, two clutch members rotatable with said shaft and movable thereon into and out of driving engagement with said gear wheels respectively, and means by which when either of said clutch members 30 is moved into the driving position the other clutch member is moved from the driving position, substantially as set forth.

35 3. In a tractor, a revoluble traction wheel having an annular rack, a motor in said wheel having a body, a main frame supported by the wheel and supporting the motor body, a driven shaft rotatable on the motor body, a supporting member adapted for travel on and to be supported by the inner

40 periphery of said wheel, resilient means supported by said member and supporting said motor body, means actuated by the motor for rotating said shaft, two gear wheels meshing with said rack and rotatable on

45 said shaft and disposed at opposite sides respectively of the axis of the wheel, and clutch mechanism by which said gear wheels may be alternately locked to said shaft, substantially as set forth.

50 4. In a tractor, a revoluble traction wheel, a motor in said wheel, driving means connecting the motor and said wheel, a main frame supported by the wheel and supporting the motor and having two abutments at

55 opposite sides respectively of the axis of said wheel, a draft frame pivoted to the main frame on a vertical axis and adapted to be swung to diametrically opposite positions in which it will respectively engage said

60 abutments, and releasable means for locking the draft frame to either of said abutments, substantially as set forth.

65 5. In a tractor, a revoluble traction wheel, a main frame supported by the wheel, driving means supported by the main frame for

rotating said wheel, and a draft frame comprising two portions hinged to each other on a horizontal axis, one portion being pivoted on a vertical axis to the main frame so as to be swung to two diametrically opposite positions with respect to the axis of the wheel, the other portion having means for lockingly engaging the main frame in either of said two positions, substantially as set forth. 70

6. In a tractor, a revoluble traction wheel, 75 a main frame supported by the wheel, means supported by said frame for rotating said wheel, a draft frame comprising two portions hinged to each other on a horizontal axis, one portion being pivoted on a vertical 80 axis to the main frame and adapted to be swung to two positions at diametrically opposite sides to the axis of said wheel, the other portion having means for being interlocked to said main frame in said two positions, and means adapted to travel on the ground for supporting said other portion, substantially as set forth. 85

7. In a tractor, a revoluble traction wheel, a main frame supported by said wheel, a 90 draft frame comprising two end portions and an intermediate portion, the intermediate portion being pivoted to the end portions respectively on horizontal axes at right angles to each other, one of said axes being 95 parallel with the axis of the wheel, one of said end portions being attached to and supported by the main frame, means adapted for travel on the ground for supporting the other end portion, means for releasably locking said intermediate portion to the main frame, and driving means carried by the main frame for rotating said wheel, substantially as set forth. 100

8. In a tractor, a revoluble traction wheel, 105 a main frame supported by said wheel, a draft frame comprising two end portions and an intermediate portion, the intermediate portion being pivoted to the end portions respectively on horizontal axes at right 110 angles to each other, one of said axes being parallel with the axis of the wheel, one of said end portions being pivoted on a vertical axis, which intersects the axis of the wheel, to said main frame, means adapted for travel on the ground for supporting said other end portion, means for releasably locking said intermediate portion to the main frame in two positions at diametrically opposite sides respectively of the axis of the 120 wheel, and means carried by the main frame for rotating said wheel, substantially as set forth. 115

9. In a tractor, a revoluble traction wheel having an annular rack, a main frame supported by the wheel and on which the latter is revoluble, a motor supported by said frame in said wheel, a driven shaft rotatable on said motor and intersecting the axis of said wheel, means actuated by the motor for 130

rotating said shaft, two gear wheels rotatable on said shaft at opposite sides of the axis of said wheel and meshing with said rack, two clutch members rotatable with said shaft and adapted to respectively have driving engagement with said gear wheels, a draft frame attached to said main frame, means adapted for travel on the ground for supporting said draft frame, and means for simultaneously moving said clutches, one to the driving and the other to the neutral position, substantially as set forth.

In testimony whereof I have signed my name to this specification.

HARRISON M. TURNER.
